UNITED STATES PATENT OFFICE.

LUTHER RINGER, OF BUFFALO, NEW YORK, ASSIGNOR TO THE SIMMEN AUTOMATIC RAILWAY SIGNAL COMPANY, OF BUFFALO, NEW YORK, A CORPORATION OF ARIZONA.

SIGNAL SYSTEM FOR SINGLE-TRACK RAILWAYS.

1,312,921.

Specification of Letters Patent.

Patented Aug. 12, 1919.

Application filed March 10, 1917. Serial No. 153,795.

To all whom it may concern:

Be it known that I, LUTHER RINGER, a citizen of the United States, residing at Buffalo, in the county of Erie and State of New York, have invented certain new and useful Improvements in Signal Systems for Single-Track Railways, of which the following is a specification.

This invention relates to a signal system for single track railways and particularly to a method for the automatic control of trains moving in opposite directions in blocks on the same track and adapted to pass each other at appropriate sidings.

There is known in the art a signal system for single track railways which in brief comprises a main block divided into a number of sub-blocks. The trains adapted to move along such a trackway are provided with signals within view of the operator which are controlled from trackside means but which signals are continuously displayed after having been once actuated from such means. Devices are also provided so that when a train enters one end of a main block the signal controlling devices set the signals for a train moving in the opposite direction at danger. These signal controlling devices are also arranged so that a train following another train will be permitted to proceed through a block under a clear signal provided it keeps a safe distance behind the train ahead.

The subject matter of this application is an improvement over the method and apparatus above described, the principal difference being that in the apparatus described herein, use is made of continuous track circuits for controlling the signal controlling devices. In the drawings, there is illustrated a preferred form of apparatus embodying the invention, the parts being shown largely in diagram and the positions of the parts on the train being those which are assumed when a clear signal has been indicated.

In the drawings, Figure 1 shows a trackway comprising a main block divided into six sub-blocks and portions of two other sub-blocks. It will of course be understood that any suitable number of sub-blocks may be employed without departing from the spirit of the invention. Fig. 2 shows the devices carried on the vehicle. In Fig. 1 there is shown a conventional representation of a train in one of the sub-blocks and the cir-

cuits are shown in the condition which would result from a train occupying such block.

The equipment along the track is as follows: The rails indicated at 194, 194 are divided by insulated joints 196 into sub-blocks B, C, D, E, F, G, J and K, the first six sub-blocks named comprising a main block A. I and H are sidings. It is assumed that movement from left to right indicates the direction of movement of an eastbound train. There is provided, at one end of each sub-block, a track battery which is connected to the rails, these several batteries being designated as 112^b, 112^c, etc., the particular sub-block to which they appertain being indicated by the lower case letter of the alphabet. At the lower end of each sub-block is a track relay, for instance 2 is a track relay for sub-block G, connected to the rails by wires 144 and 145. 1 is the track relay for sub-block F, connected to the rails by wires 146 and 147; 5 is the track relay for sub-block E connected to the rails by wires 148 and 149; 6 is the track relay for sub-block D connected to the rails by wires 150 and 151; 11 is the track relay for the sub-block C and is connected to the rails by the wires 152 and 153; and 12 is the track relay for sub-block B and is connected to the rails by wires 154 and 155. There are also provided control relays 3 and 13 and auxiliary relays 4 and 14. When there is no train in the block, the relays 1, 2, 3, 5, 6, 11, 12 and 13 are energized by circuits which will be hereinafter described, and the relays 4 and 14 are deenergized.

On one side of the track there are provided westbound signal rails numbered respectively 101, 102, 103, 104, 105, 106, 107, 108, 109, 110 and 111, and on the other side of the track a similar series of eastbound signal rails numbered respectively, 201, 202, 203, 204, 205, 206, 207, 208, 209, 210, 211. The signal rail 101 is located adjacent to the track rails of the siding I, and the signal rail 102 is located adjacent to the main track at the left end of sub-block K, which is the exit end of such block for westbound trains. A signal rail 103 is located at the exit end of sub-block G. Signal rails 104 and 105, which are distant and home rails, are located near and at the exit end of sub-block F. Signal rails 106 and 107 are similarly located near the exit end of sub-block E; signal rails 108 and 109 near the exit end of

sub-block D; and signal rails 110 and 111 near the exit end of sub-block C. The east-bound signal rails are similarly located. 201 and 202 are related to sub-block J, 203 to 5 sub-block B, 204 and 205 to sub-block C, 206 and 207 to sub-block D, 208 and 209 to sub-block E and 210 and 211 to sub-block F. When no train is in the block all of the signals are normally energized through circuits 10 which are hereinafter described. It will be understood of course that instead of signal rails located at the entrances of the various sub-blocks, fixed signals may be employed. It will be obvious to anyone skilled in this 15 art that the act of energizing the signal rail so that a car passing over it will receive a clear signal is equivalent to energizing a fixed signal to hold it clear, and likewise that deenergizing a signal rail so that a car 20 passing over it will receive a danger signal is equivalent to deenergizing a fixed signal to permit it to assume a danger position by gravity.

Two electrical conductors or wires designated 29 and 30 run the entire length of the trackway and are connected at suitable intervals to batteries, such as 15 and 16. The wire 30 is connected to the positive terminals of batteries 15 and 16 by the wires 39 25 and 49 respectively. The wire 29 is connected to the negative terminals of batteries 15 and 16 by the wires 40 and 50 respectively. The wire 29 is connected to one track rail in each sub-block by a wire and a resistance coil. Such a connection for the sub-blocks C and D consists of the wire 69 and the resistance coils 113^c and 113^d.

The relays and their circuits will now be described. The track relay 2 has five neutral armatures 41, 42, 43, and 44 adapted 40 when the relay is energized to touch contacts 81, 82, 83 and 84, and armature 45 to touch contact 85 when the relay is deenergized, the energization of the relay being 45 normally accomplished by means of the track battery 112^e. The track relay 1 has six neutral armatures 21, 22, 23 and 24 adapted when the relay is energized to touch contacts 61, 62, 63 and 64, and armatures 25 50 and 26 adapted to touch contacts 65 and 66 when the relay is deenergized, the relay being normally energized by the track battery 112^f. The track relay 5 has four neutral armatures 17, 18, 19 and 20 adapted when the 55 relay is energized to touch contacts 117, 118, 119 and 120 respectively, this relay being normally energized by the track battery 112^e. The relay 6 is similar to the relay 5; it is normally energized by the track battery 60 112^d and has four neutral armatures 7, 8, 9 and 10 adapted when the relay is energized to touch contacts 127, 128, 129 and 130 respectively. The track relay 11 is similar to the relay 1 and is normally energized by the 65 track battery 112^c; it has six neutral arm-

tures 31, 32, 33 and 34 adapted to touch contacts 71, 72, 73 and 74 respectively when the relay is energized, and armatures 35 and 36 adapted to touch contacts 75 and 76 when the relay is deenergized. The track relay 12 70 is similar to the relay 2 and is energized from the track battery 112^b. It has five neutral armatures 51, 52, 53 and 54 adapted to touch contacts 91, 92, 93 and 94 respectively when the relay is energized, and armature 55 75 adapted to touch contact 95 when the relay is deenergized. The auxiliary relay 4 has three neutral armatures 46, 47 and 48 adapted when the relay is energized, to touch contacts 86, 87 and 88 respectively. This relay 80 is normally deenergized and the circuits whereby it is energized will be traced during the description of the mode of operation of the apparatus.

The control relay 3 has two neutral armatures 27 and 28, which are adapted, when the relay 3 is energized, to touch the contacts 67 and 68 respectively. The relay 3 is normally energized through the following circuit: from the positive side of the battery 15 to the wires 39, 30, 79 and 181, armature 52, contact 92, wire 190, armature 34, contact 74, wire 192, armature 10, contact 130, wire 163, armature 20, contact 120, wire 160, contact 64, armature 24, wire 198, 85 relay 3, wire 200, wire 116, wire 29, wire 40 to the negative side of the battery 15. An auxiliary circuit for holding the relay 3 energized under certain circumstances, provided it is already energized, may be traced 90 as follows: from the positive side of the battery 16 to the wires 49, 30, 121, and 137, armature 44, contact 84, wire 131 and wire 134, armature 27, contact 67, wire 199, relay 3, wires 200 and 116, wires 29 and 50 to the 100 negative side of battery 16.

The control relay 13 is similar to the relay 3. It has two neutral armatures 37 and 38, which are adapted, when the relay 13 is energized, to touch contacts 77 and 78 respectively. The relay is normally energized through a circuit from the positive side of battery 16 to the wires 49, 30, 121, and 139, armature 42, contact 82, wire 140, armature 23, contact 63, wire 159, contact 119, armature 19, wire 162, contact 129, armature 9, wire 191, contact 73, armature 33, wire 176, relay 13, wire 177, wire 80, wire 29 and wire 50 to the negative side of the battery 16. An auxiliary circuit for holding the relay 110 13 energized under certain conditions, provided it is already energized, may be traced as follows: from the positive side of battery 15 to the wires 39, 30, 79 and 183, armature 54, contact 94, wire 173, wire 189, armature 37, contact 77, wire 175, relay 13, wire 177, wire 80, wire 29, wire 40 to the negative side of the battery 15.

It will be understood that, as before described, one main rail of each sub-block is 130

connected to the negative side of batteries 15 and 16 through the common wire 29, the wires 59, 60, 69, etc. and the resistance coils 113^c, 113^d, etc. It will be obvious that when 5 the signal rails are connected to the positive side of the batteries 15 and 16, a partial circuit will be provided which may be closed by means of the vehicle carried circuits. The circuits by which the various signal 10 rails are normally connected to the positive side of the batteries 15 and 16 will be traced.

The circuit for the signal rails 101, 102, and 103 is as follows: from the positive side 15 of the battery 15 to the wire 39, wire 30, wires 79 and 182, armature 53, contact 93, wire 171, armature 38, contact 78, wire 230, wire 89, contact 61, armature 21, wires 142 and 143 to the signal rails 101, 102, and 103. The circuit for the signal rails 104 20 and 105 is as follows: from the positive side of the battery 15 to the wires 39, 30, 79, and 182, armature 53, contact 93, wire 171, armature 38, contact 78, wire 230, wire 89, wire 114, armature 17, contact 117, wire 25 231 to the signal rails 104 and 105. The circuit for the signal rails 107 and 106 is as follows: from the positive side of the battery 15 to the wires 39, 30, 79, and 182, armature 53, contact 93, wire 171, armature 38, contact 78, wire 230, wire 89, wire 99, armature 7, contact 127, wire 232, wire 233 to signal rails 106 and 107. The circuit for the signal rails 108 and 109 is as follows: from the positive side of the battery 15 to the wires 39, 30, 79 and 182, armature 53, contact 93, wire 171, armature 38, contact 78, wire 230, wire 89, wire 235, armature 51, contact 91, wire 40 169, wire 170 to signal rails 110 and 111. The circuit for the signal rails 110 and 111 is as follows: from the positive side of the battery 15 to the wires 39, 30, 79 and 182, armature 53, contact 93, wire 171, armature 38, contact 78, wire 230, wire 89, wire 235, armature 51, contact 91, wire 45 169, wire 170 to signal rails 110 and 111.

The energization of the eastbound signal rails is controlled in a manner similar to the energization of the westbound signal rails just described. Now follows a description in detail of the circuits for the eastbound signal rails. The circuit for the signal rails 201, 202, and 203 is as follows: from the positive side of the battery 16 to the wires 49, 30, 121, 138, armature 43, contact 83, wire 122, armature 28, contact 68, wire 236, wire 90, wire 100, contact 128, armature 8, wire 165, and wire 166 to the signal rails 204 50 and 205. The circuit for the signal rails 206

and 207 is as follows: from the positive side of battery 16 to the wires 49, 30, 121 and 138, armature 43, contact 83, wire 122, armature 28, contact 68, wire 236, wire 90, wire 115, contact 118, armature 18, wire 161 70 and wire 164 to signal rails 206 and 207. The circuit for the signal rails 208 and 209 is as follows: from the positive side of the battery 16 to the wires 49, 30, 121 and 138, armature 43, contact 83, wire 122, armature 28, contact 68, wires 236, 90, and 234, contact 62, armature 22, wires 157 and 158 to signal rails 208 and 209. The circuit for the signal rails 210 and 211 is as follows: from the positive side of the battery 16 to the wires 49, 30, 121 and 138, armature 43, contact 83, wire 122, armature 28, contact 68, wire 236, wire 90, armature 41, contact 81, wire 141, and wire 156 to signal rails 210 and 211.

In Fig. 2 there is shown the car equipment. In this figure, 194, 194 indicate the track rails, 195, 195 the wheels of the vehicle and 197 its axle. 212 is a shoe hingedly mounted at a convenient place on the vehicle and adapted to contact with the signal rails 90 101, 102, etc. During such contact with a signal rail, the shoe breaks contact with the contact point 221, and after leaving such signal rail is restored by gravity or spring pressure to its contact point. 213 is a signal 95 relay on the vehicle. The relay 213 has a neutral armature 217, which is adapted, when the relay 213 is energized, to touch the contact points 218 and 219; and when the relay 213 is deenergized, the armature 217 is 100 adapted to touch the contact point 229. 216 is a local battery mounted on the vehicle. 214 is a clear signal or green light. 215 is a danger signal or red light. The parts described are suitably connected by electrical 105 wires or conductors, which will be more fully described in connection with the description of the electrical circuits hereinafter.

The operation of the car-carried devices is as follows: When the vehicle is standing 110 with its shoe 212 on a signal rail, which is connected to one terminal of a battery, the other terminal of the battery being connected to one of the track rails, current flows through a circuit from one terminal of the 115 battery to the signal rail, the shoe 212, wire 220, relay 213, wires 238 and 224, axle 197, wheels 195, rail 194 to the other terminal of the battery. This causes the clear signal or green light 214 to glow through a circuit from the positive side of the battery 216 to the wire 226, armature 217, contact 218, wire 227, green light 214, and wires 239 and 225 to the negative side of the battery 216. After leaving an energized signal rail, the 120 shoe 212 will be restored to its contact 221, and the relay 213 will remain energized through the following holding circuit: from the positive side of the battery 216 to the wire 226, armature 217, contact 219, wire 125 130

223, contact 221, shoe 212, wire 220, relay 213, wire 238 and wire 225 to the negative side of the battery 216. It is thus seen that after leaving an energized signal rail the 5 green light continues to burn.

When the vehicle is in such a position that its shoe 212 is resting upon a deenergized signal rail, the holding circuit will be broken at the contact 221, and the relay 213 10 will become deenergized, causing the danger signal or red light 215 to burn through the following circuit: from the positive side of the battery 216 to the wire 226, armature 217, contact 229, wire 228, red light 215, 15 wire 230, wire 225 to the negative side of the battery 216. After leaving a deenergized signal rail, the relay 213 will remain deenergized as its holding circuit is broken at the contact 219 and the red light will continue 20 to burn.

The following is a description of the operation of the track controlling circuits, assuming that a train is passing through the main block A in the westbound direction, 25 that is, from right to left. Let us first assume that the train is in the sub-block G. If there is no other train in the main block A, the signal rails 101, 102 and 103 will have been energized and the train will have received a clear signal. As soon as the train enters the sub-block G, the track relay 2 becomes deenergized, as the wheels of the train short circuit the battery 112^a. This causes the armatures operated by the relay 30 2 to drop and all of the eastbound signal rails 201, 202, 203, 204, 205, 206, 207, 208, 209, 210 and 211 to become deenergized as their energizing circuit is now broken at the contact 83. Therefore, if an eastbound 40 train should attempt to enter the main block A, it will receive a danger signal in the cab.

Let us now assume that the train has advanced into the sub-block F. As soon as the train has cleared the sub-block G, the 45 track relay 2 will again become energized, but as soon as it enters the sub-block F, the track relay 1 will become deenergized due to the short circuiting of the track battery 112^f by the wheels of the train. Due to the 50 fact that when the train was in the sub-block G, the auxiliary holding circuit of the control relay 3 was broken at the contact 84, the progress of the train into sub-block F thereby breaking the operating circuit of the control relay 3 at the contact 64, causes 55 the relay 3 to become deenergized. After the train has cleared the sub-block G and the contact 84 is again touching the armature 44, the control relay 3 does not again 60 become energized as its auxiliary holding circuit is now open at its own contact 67. And consequently, in spite of the fact that after the train is clear of the sub-block G, contact 83 again touches armature 43, the 65 east-bound signal rails 201, 202, 203, 204,

205, 206, 207, 208, 209, 210 and 211 are not energized again, as their energizing circuit is now open at the contact 68. It will also be observed that as soon as the train enters the sub-block F, the westbound signal rails 70 101, 102, and 103 become deenergized as their energizing circuit is broken at the contact 61.

Let us now assume that the train has advanced into the sub-block E. As soon as this occurs, the track relay 5 becomes deenergized due to the short circuiting of the track battery 112^e by the wheels of the train. After the train has cleared the rails of sub-block F, the track relay 1 again becomes energized, but the control relay 3 is not 80 again energized as its operating circuit is now open at the contact 120. The eastbound signal rails 201, 202, 203, 204, 205, 206, 207, 208, 209, 210 and 211 will therefore 85 still be deenergized, as their energizing circuit is still open at the contact 68. When the train has advanced into sub-block E and cleared sub-block F, the westbound signal rails 101, 102 and 103 will again be energized due to the closing of the contact 61, 90 but the westbound signal rails 104 and 105 will be deenergized due to the opening of their energizing circuit at the contact 117.

Let us now assume that the train has advanced into the sub-block D. As soon as 95 the train enters this sub-block, the track relay 6 will become deenergized due to the short circuiting of the battery 112^d by the wheels of the train. As soon as the train has advanced far enough into the sub-block 100 D for its wheels to clear the sub-block E, the track relay 5 will again be energized, but this will not again energize the control relay 3 as its operating circuit is now broken at the contact 130, and therefore the eastbound signal rails 201, 202, 203, 204, 205, 206, 207, 208, 209, 210, and 211 will still be 105 deenergized as their energizing circuit will still be open at the contact 68. When the track relay 5 again becomes energized, the 110 westbound signal rails 104 and 105 will again become energized through the contact 117, but as long as the train is in the sub-block D, the westbound signal rails 106 and 107 will be deenergized as their energizing 115 circuit is open at the contact 127.

Let us now assume that the train has advanced into sub-block C. This will cause track relay 11 to become deenergized. As soon as the train has passed far enough into 120 the sub-block C for its wheels to clear the sub-block D, the track relay 6 will again become energized. This will not, however, cause the control relay 3 to again become energized as its operating circuit is now open 125 at the contact 74, and the east bound signal rails 201, 202, 203, 204, 205, 206, 207, 208, 209, 210 and 211 will still be deenergized, as their energizing circuit will still be open at contact 68. As soon as the track relay 6 130

again becomes energized, the westbound signal rails 106 and 107 will again become energized due to the closing of their energizing circuit at the contact 127, but the westbound signal rails 108 and 109 will become deenergized as soon as the train enters sub-block C due to the opening of their energizing circuit at the contact 71. The deenergization of the track relay 11 breaks the operating circuit of the control relay 13 at the contact 73, but the relay 13 does not become deenergized as its auxiliary holding circuit is still closed at the contacts 94 and 77. The deenergization of the track relay 11 results in the energization of the auxiliary relay 14 through a circuit from the positive side of the battery 15 to the wire 39, wire 30, wire 79, wire 183, armature 54, contact 94, wires 173 and 240, contact 75, armature 35, wire 178, relay 14, wires 177, 80, 29 and 40 to the negative side of the battery 15.

Let us now assume that the train has advanced into the sub-block B. As soon as the train enters this sub-block the track relay 12 becomes deenergized due to the short circuiting of the track battery 112^b. As soon as the train has advanced far enough into the sub-block B for its wheels to clear the sub-block C, the track relay 11 becomes again energized. This does not, however, cause the control relay 3 to become again energized as its operating circuit is now open at the contact 92. The eastbound signal rails 201, 202, 203, 204, 205, 206, 207, 208, 209, 210 and 211 will therefore still be deenergized, as their energizing circuit will still be open at the contact 68. As soon as the track relay 11 again becomes energized, the westbound signal rails 108 and 109 are again energized by the closing of the contact 71, but the westbound signal rails 110 and 111 become deenergized as soon as the train enters the sub-block B as their energizing circuit is now open at the contact 91. Although when the train is in the sub-block B and clear of the sub-block C, the operating circuit heretofore described for the auxiliary relay 14 is now broken at the contact 75 due to the energization of the track relay 11 and at the contact 94 due to the deenergization of the track relay 12, the auxiliary relay 14 does not become deenergized as an auxiliary holding circuit for this relay is formed as follows: from the positive side of the battery 15 to the wires 39, 30, 79 and 184, armature 55, contact 95, wire 186, wire 241, armature 56, contact 96, wire 174, relay 14, wire 177, wire 80, wire 29, and wire 40 to the negative side of the battery 15. While the train is occupying a part of sub-block B and a part of sub-block C, it will be observed that the operating circuit of the control relay 13 is open at the contact 73 due to the deenergization of the track relay 11, and also that the auxiliary holding circuit of the

control relay 13, which has heretofore been traced, is open at the contact 94 due to the deenergization of the track relay 12. The control relay 13 will not, however, become deenergized due to the closing of a second auxiliary holding circuit as follows: from the positive side of the battery 15 to the wires 39, 30, 79 and 187, armature 57, contact 97, wires 173 and 189, armature 37, contact 77, wire 175, relay 13, wire 177, wire 80, wire 29 and wire 40 to the negative side of the battery 15.

It will be noted that when the track relay 12 is deenergized, the energizing circuit of the westbound signal rails 101, 102, 103, 104, 105, 106, 107, 108, 109, 110 and 111 is open at the contact 93. However, due to the fact that the auxiliary relay 14 is now energized, this circuit is completed by the wire 172, contact 98 and armature 58, and the westbound signal rails are not deenergized except as heretofore described.

Let us now assume that the train has passed entirely out of the main block A whereupon the track relay 12 will again become energized. This will cause the control relay 3 to again become energized due to the closing of its operating circuit at the contact 92. This causes the eastbound signal rails 201, 202, 203, 204, 205, 206, 207, 208, 209, 210 and 211 to again become energized due to the closing of their energizing circuits at the contact 68. The westbound signal rails 110 and 111 will again become energized due to the closing of their energizing circuit at the contact 91. The auxiliary relay 14 will again become deenergized due to the breaking of its holding circuit at the contact 95. Thus all the parts are restored to their normal condition.

It is not considered necessary to give a detailed description of the progress of an eastbound train through the block, as it will readily be understood that when an eastbound train starts through the main block, the control relay 13 will become deenergized, thus deenergizing all of the westbound signal rails 101, 102, 103, 104, 105, 106, 107, 108, 109, 110 and 111, and this condition will exist until the train has passed through the entire main block. It will be obvious that the purpose of auxiliary relays 4 and 14 and their cooperating circuits is to prevent a train leaving the block, from deenergizing the control relays 3 and 13 respectively, the same as a train entering a block would.

From this description, the advantages of the herein-described invention will be obvious to those skilled in the art. It will be observed that full protection for main blocks is given for opposing trains, but following trains may follow each other through the block with adequate information as to how close they are approaching the preceding train.

I claim:—

1. In a signal system for single track railways, a main block, comprising a plurality of sub-blocks, a normally closed track circuit including a source of current and a track relay for each sub-block, a signal for each direction for each sub-block, and a neutral control relay at one end of the main block for controlling all of the signals for one direction.
2. In a signal system for a single track railway, a block comprising a plurality of sub-blocks, a normally closed track circuit including a source of current and a track relay for each sub-block, a signal for each direction for each sub-block, a neutral control relay at one end of the principal block for controlling all of the signals for one direction, and a corresponding neutral control relay at the other end of the principal block for controlling all of the signals for the opposite direction.
3. In a signal system for single track railways, a main block comprising a plurality of sub-blocks, a normally closed track circuit including a source of current and a track relay for each sub-block, a signal for each direction for each sub-block, and a neutral control relay at one end of the main block for controlling all of the signals for traffic moving from the other end of the main block toward said control relay.
4. In a signal system for single track railways, a main block comprising a plurality of sub-blocks, a normally closed track circuit including a source of current and a track relay for each sub-block, a signal for each direction for each sub-block, a neutral control relay at one end of the main block for controlling all of the signals for traffic moving from the other end of the main block toward said control relay, and a corresponding neutral control relay at the other end of the block for controlling all of the signals for traffic moving in the opposite direction.
5. In a signal system for single track railways, a main block comprising a plurality of sub-blocks, a normally closed track circuit including a source of current and a track relay for each sub-block, a signal for each direction for each sub-block, a normally energized neutral control relay at one end of the main block for controlling all of the signals for one direction, and means for setting at danger the said signals when said relay is deenergized.
6. In a signal system for single track railways, a main block comprising a plurality of sub-blocks, a normally closed track circuit including a source of current and a track relay for each sub-block, a signal for each direction for each sub-block, a normally energized neutral control relay at one end of the main block for controlling all of the signals for the other direction, means for deenergizing said relay when a train enters the block at the end where said relay is located, a corresponding normally energized neutral control relay at the other end of the main block for controlling all of the signals for one direction, and means for deenergizing said relay when a train enters the block at the end where said relay is located.
7. In a signal system for single track railways, a main block comprising a plurality of sub-blocks, a normally closed track circuit including a source of current and a track relay for each sub-block, a signal for each direction for each sub-block, a normally energized neutral control relay at one end of the main block for controlling all of the signals for one direction, and means for deenergizing said relay when a train enters the block at the end where said relay is located.
8. In a signal system for single track railways, a main block comprising a plurality of sub-blocks, a normally closed track circuit including a source of current and a track relay for each sub-block, a signal for each direction for each sub-block, a normally energized neutral control relay at one end of the main block for controlling all of the signals for one direction, means for deenergizing said relay when a train enters the block at the end where said relay is located, a corresponding normally energized neutral control relay at the other end of the main block for controlling all of the signals for the opposite direction and means for deenergizing said relay when a train enters the block at the end where said relay is located.
9. In a signal system for single track railways, a main block comprising a plurality of sub-blocks, a normally closed track circuit for each sub-block, a signal for each direction for each sub-block, a normally energized neutral control relay at one end of the main block for controlling all of the signals for one direction, means for deenergizing said relay when a train enters the block at the end where said relay is located, and means for maintaining said relay deenergized until said train leaves the block.
10. In a signal system for single track railways, a main block comprising a plurality of sub-blocks, a normally closed track circuit for each sub-block, a signal for each direction for each sub-block, a normally energized neutral control relay at one end of the main block for controlling all of the signals for one direction, means for deenergizing said relay when a train enters the block at the end where said relay is located, means for maintaining said relay deenergized until said train leaves the block, a corresponding normally energized neutral control relay at the other end of the main block for controlling all of the signals for the other direction, means for deenergizing said relay when a train enters the block at the end where said relay is located, and means for maintaining said relay deenergized until said train leaves the block.

said relay when a train enters the block at the end where said relay is located and means for maintaining said relay deenergized until said train leaves the block.

- 5 11. In a signal system for single track railways, a main block comprising a plurality of sub-blocks, a normally closed track circuit including a source of current and a track relay for each sub-block, a signal for 55 each direction for each sub-block, a normally energized neutral control relay at one end of the main block for controlling all of the signals for one direction, and means for maintaining said relay energized when a train leaves the block at the end where said 60 relay is located.
- 10 12. In a signal system for single track railways, a main block comprising a plurality of sub-blocks, a normally closed track circuit including a source of current and a track relay for each sub-block, a signal for 65 each direction for each sub-block a normally energized neutral control relay for controlling all of the signals for one direction, means for deenergizing said relay when 70 a train enters the block at the end where said relay is located and means for maintaining said relay energized when a train leaves the block at the end where said 75 relay is located.
- 15 13. In a signal system for single track railways, a main block comprising a plurality of sub-blocks a normally closed track circuit including a source of current and a track relay for each sub-block, a signal for 80 each direction for each sub-block, a normally energized neutral control relay at one end of the main block for controlling all of the signals for one direction, means for maintaining said relay energized when a train leaves the block at the end where said relay is located.
- 20 14. In a signal system for single track railways, a main block comprising a plurality of sub-blocks, a normally closed track circuit including a source of current and a track relay for each sub-block, a signal for 85 each direction for each sub-block, a normally energized neutral control relay for controlling all of the signals for one direction, means for deenergizing said relay when 90 a train enters the block at the end where said relay is located, means for maintaining said relay energized when a train leaves the block at the end where said relay is located, a corresponding normally energized neutral control relay at the other 95 end of the main block for controlling all of the signals for the other direction, and means for maintaining said relay energized when a train leaves the block at the end where said relay is located.
- 25 15. In a signal system for single track railways, a main block comprising a plurality of sub-blocks, a normally closed track circuit for each sub-block, a signal for each direction for each sub-block, a normally 100 energized neutral control relay at one end of the main block for controlling all of the signals for one direction, and means including a normally deenergized auxiliary relay for maintaining said control relay energized when a train leaves the block at the end where said relays are located.
- 30 16. In a signal system for single track railways, a main block comprising a plurality of sub-blocks a normally closed track circuit for each sub-block, a signal for each direction for each sub-block, a normally energized neutral control relay for controlling all of the signals for one direction, means for deenergizing said relay when 105 a train enters the block at the end where said relay is located, means for maintaining said relay energized when a train leaves the block at the end where said relay is located, a corresponding normally energized neutral control relay at the other end of the main block for controlling all of the signals for the opposite direction, means for deenergizing said relay when a train enters the block at the end where said relay is located and means for maintaining said relay energized 110 when a train leaves the block at the end where said relay is located.
- 35 17. In testimony whereof I affix my signature in presence of two witnesses.

LUTHER RINGER.
